SEDGWICK N. WIGHT, OF ROCHESTER, NEW YORK, ASSIGNOR TO GENERAL RAILWAY SIGNAL COMPANY, OF GATES, NEW YORK, A CORPORATION OF NEW YORK.

ABSOLUTE PERMISSIVE BLOCK-SIGNAL SYSTEM.

1,134,982.

Specification of Letters Patent.

Patented Apr. 6, 1915.

Application filed July 8, 1911. Serial No. 637,457.

To all whom it may concern:

Be it known that I, SEDGWICK N. WIGHT, a citizen of the United States, and resident of the city of Rochester, in the county of 5 Monroe and State of New York, have invented a new and useful Improved Absolute Permissible Block-Signal System, of which the following is a specification.

This invention has to do with railway signals and particularly with that class designed to afford a permissive indication.

Systems of track circuit controlled automatic block signals heretofore installed on railways are designed to maintain a safe 10 space interval between trains on the same trackway, whether on a single or multiple track line, by having each one of a series of suitably located signals indicate the occupancy or non-occupancy of a predetermined 15 section of the trackway. Great variations exist in the kind of signals used. For example there is the one arm signal capable of display in one set position and one operated position only, this signal being capable 20 therefore of giving two indications only, these indications being differently construed according as the signal is a home signal or a distant signal. Then there is another one arm signal capable of display in 25 one set position and two operated positions and therefore capable of giving all the indications provided by two one arm signals. There is further a two arm signal each arm being capable of display in one set and one 30 operated position, and therefore, capable of giving the same indications provided by a one arm, three position signal. Similar great variations exist in the character of the circuits controlling these various 35 signals, from which we have what are commonly known as the simple overlap scheme without distant signals; the overlapping scheme with an occasional distant signal; the home and distant or the three position 40 scheme without overlap; the home and distant or the three position scheme with overlap—and other schemes. But while in track circuit controlled automatic block signalling practice all the above named and many other 45 differences exist, each and every one of all the varieties in use is characterized by the following distinctive feature, viz:—that whenever a train occupies any given track circuit section, the aspect of the particular 50 signal whose circuit is affected or controlled

by the relay of that track circuit section, is in no wise dependent upon the manner in which such train entered the block; that is to say, the aspect of the signal will be the same, under the condition noted, regardless 55 of whether the train moved into the block of which the occupied track circuit forms a part, at that end of the block where the signal is placed or at the opposite end. In consequence of this characteristic of all 60 block systems of the kind above described, many railways suffer great annoyance, inconvenience and loss of time, as for example wherever single track lines have employed such a block system, in all such cases, an 65 engineer finding a signal displaying that aspect which indicates that a section of track governed by that signal is occupied by another train, has no means of knowing whether such other train entered the block 70 from the direction his train is pursuing or from the other end of said block. In general, under such conditions such engineer would be required in the interest of safety to bring his train to a stop at the 75 signal and to remain there until a flagman goes a long distance ahead of him, whereupon he would be permitted to follow such flagman at a speed regulated by that of the 80 flagman until he passes through the block. 85 In many locations this operation not only entails such loss of time, but puts the train in danger of being wholly stalled or of breaking in two,—all of which inconveniences and dangers could be prevented if a 90 system of block were employed in which one aspect of the signal is shown when the block is occupied by a train that moved into the block at one end thereof and in which another aspect of the signal is shown when any 95 part of the same block is occupied by a train that moved into the block from the opposite end thereof. The term "block" as used above is meant to designate that part of a 100 railway between two signals which govern the movement of traffic in the same direction. Certain systems of single track automatic block have been proposed in which opposed movements of trains are governed by signals situated at the ends of sections of 105 single track; the space between these two opposing signals being signaled for following trains in both directions in the usual manner. In such systems the two entrance signals are usually interlocked one with the 110

other so that when one gives the proceed indication the other must give the stop position and in consequence of the intermediate signals the entrance signals will at times give an indication to a following train which, if one were fully conversant with the circuits involved would enable them to deduce the fact that a train was in a certain part of the single track section and that it had entered that part from a certain direction. To speak more positively, this indication of direction is only given while a train is on one of the blocks and before or after the said train enters this particular block there is no indication of the direction of its movement or even the fact that the train is present at all on any part of the intervening space. There has also been invented a system of track circuit control for automatic block signals capable of a plurality of aspects, one of which is a normal bias aspect as usual and the other or others, operated aspects, whereby a train entering upon a predetermined section of track from one end will cause the signal to display its normal bias aspect and entering upon the same predetermined section from the other end will cause the display of an operated aspect. That invention consists primarily of a signal circuit adapted to be opened by a train on the track circuit sections of a block, and of a further signal circuit adapted to be closed by a train which enters the block from one direction but is prevented from closing by a train which enters the block from the other direction.

The primary object of the present invention is to obviate the need for certain electrical adjustments necessitated by the arrangement and combinations of the above mentioned invention.

This invention will be more fully described hereinafter with reference to the form thereof herein illustrated and which I have selected as an example for the purpose of explaining the principles involved, it being understood that the invention may be embodied in various forms and arrangements of apparatus.

In the accompanying drawing appear reference characters which are referred to in this specification, which will more fully explain the invention.

Figure 1 is a schematic view illustrating my invention applied as a "normal danger" system; Fig. 2 is a schematic view illustrating my invention applied as a "normal clear" system.

Construction.—Referring to Fig. 1, 1 and 2 designate rails of a track which are divided into sections A, B and C, by means of insulation at the points 3, B and C forming a block controlled by signal 10; 4, 5 and 6 designate relay coils the ends of which are connected to the rails of the respective section

A, B and C; 7, 8 and 9 designate batteries the terminals of which are connected to the two rails of the respective sections A, B and C; 10 designates a signal placed at the entrance to section B and controlling the entrance thereto by reason of the distinctive positions which the arm thereof may be caused to assume; 4¹ designates an armature controlled by relay coil 4, being held in the upper position as shown when the track circuit formed by the battery 7, the track rails 1 and 2 and the coil 4 are intact, and no train or other means for shunting battery 7 are present upon the rails of block section A; similarly 5¹, 5² and 6¹ designate armatures which are controlled by the relay coils 5 and 6; 11 designates a relay coil which controls armature 11¹, which, in the energized condition of coil 11¹ is in the position as shown; 12 designates a relay coil which controls armatures 12¹ and 12² and which in the normal condition of the system, are in the inclined position as shown, as the relay coil 12 is normally deenergized; 13 designates a battery which is intended to furnish current for the energization of relay coil 11; 14 designates a battery which serves as a source of energy for the operation of signal 10, and also as a means for furnishing energy to relay coil 12; 15 designates a circuit breaker which is designed to move in unison with the arm of the signal 10, and in order to indicate that it does so move, it has been shown in the diagrammatic view as being connected with the arm of the signal 10 by means of the rod 16.

In the diagrammatic view accompanying this specification no details of a specific means for moving the arm of the signal 10 have been shown or described, for such means are well known and understood by those skilled in the art and it suffices in describing this invention to represent the signal and the controlling wires therefor diagrammatically, for it is well understood by those skilled in the art how, by the use of the same control wires represented by the applicant, a one arm signal may be moved to two operated positions and also how by the same control wires two one-arm signals can be each moved to an operated position, so that for the purposes of this invention it is immaterial whether a single arm signal is used or whether a two arm signal is used, for, in either case a plurality of aspects may be obtained to which identical interpretations should be given.

Operation.—With no train on any part of the track represented in the diagram, all of the parts would be in what is called the normal position as shown in the drawing. If a train should approach moving in the direction of the arrow D as soon as the first pair of wheels passed upon the rails 1 and 2, the current from battery 7 would be shunted

from the relay coil 4, consequently the armature 4¹ would fall and make contact with the wire 17, current would then flow from the positive side of the battery 14 in the following path: wires 18, 19 and 20, armature 11¹, wire 21, signal 10, wire 17, armature 4¹, wires 22, 23, 24 and 25 to the negative terminal of the battery 14. It will be noticed that the path above traced has two points at which a possible break may occur, namely, armature 4¹ and armature 11¹, but with no train upon any one of the block sections A, B, C, the armature 11¹ would be in the upper position as shown and so make contact with wire 21 as relay 11 would be energized by reason of current flowing in the following path, positive side of battery 13, wire 26, armature 6¹, wire 27, armature 5¹, wire 28, relay coil 11, wires 29, 30, 24 and 31 to the negative terminal of the battery 13. The relay armature 4¹ having made contact with wire 17 as heretofore described, and current being caused to flow to the signal by means of wire 21, the arm of the signal 10 will be raised to the full clear or 90° position in a manner well known and understood by those skilled in the art, and, as current flowing in wire 21 does cause arm of signal 10 to move to the full clear or 90° position, the wire 21 will be called hereafter the 90° control wire although as heretofore observed the signal 10 may have 2 arms in which case the wire 21 would be a control wire for the operated position of the upper arm and would cause that upper arm to be moved to any desired position. By reason of the movement of the arm of signal 10 as heretofore described, a train upon reaching the entrance to the section B, will receive a clear signal and will so enter the section B at full speed. As soon as the first wheels of the first truck pass upon the rails 1 and 2 of section B, current from the battery 8 is shunted from relay 5, consequently the armatures 5¹ and 5² are dropped. The armature 5¹ by dropping breaks contact with the wire 27, consequently the current flowing from the battery 13 in the heretofore traced circuit has no longer a path open to it through the relay coil 11, consequently the armature 11¹ is allowed to drop and remains in its lower position just so long as any of the wheels of the train are upon the rails 1 and 2. The deenergization of relay 1 and the consequent dropping of armature 1¹, breaks the connection between armature 1¹ and wire 21, consequently current ceases to flow through the 90° control wire 21 and the arm of the signal 10, which was in the clear position, falls by gravity in the well known manner to the danger position, but the same action upon relay 5 which caused signal arm to fall to the danger position also caused the armature 5² to drop and to form a circuit in which current flows as follows; remembering that in the clear position of the

signal the arm 15 makes contact with the contact 33; positive side of battery 14, wires 18, 19 and 24, arm 15, contact 33, wire 35, armature 5², wires 36 and 37, relay coil 12, wires 38, 30 and 25 to the negative terminal of the battery 14. The current in the above traced path passing through relay coil 12 would energize the same and cause the armatures 12¹ and 12² to be raised to their upper positions and the instant the armature 12¹ is raised to its upper position another circuit would be formed, called technically, a "stick" circuit which would continue the relay coil energized even though the just above traced circuit were broken, the circuit alluded to being as follows: positive terminal of battery 14, wires 18, 19 and 20, armature 11¹, which it must be remembered is in its lower position, wire 32, armature 12¹, which is now in its upper position, wires 39 and 37, relay coil 12, wires 38, 30 and 25 to the negative terminal of the battery 14. It will be readily seen that the last above traced circuit is entirely independent of the circuit through the breaker 15 which is moved in unison with the arm of the signal 10, so, although it is necessary to first have a circuit formed through the breaker 15 and the relay armature 5² in order to energize the relay coil 12, after the relay coil has once been energized and the armature 11¹ is in its lower position it will remain energized even though the circuit breaker 15 is moved to the position shown in the figure out of contact with contact 33 by the movement of the arm of the signal 10 to the danger position. It will be noticed that two conditions precedent were necessary to be fulfilled before relay coil 12 could be initially energized, which conditions were first: the movement of the arm of signal 10 to the full clear position thus closing contact between arm 15 and strip 33; second: the subsequent dropping of armature 5² by the entrance of a train upon block section B. As such conditions are necessary for the initial energization of relay coil 12 and as such conditions can only arise by the movement of a train on to and through section A onto section B, therefore the relay 12 cannot be initially energized by the movement of a train onto and through section C onto section B, for in case the latter movement takes place, when the wheels of the train come upon the rails of section B one condition necessary for the initial energization of relay coil 12 is not present, namely, the contact between arm 15 and contact 33, for it is necessary that a train be upon section A in order to clear the signal 10. A movement of a train in the direction of the arrow E upon to section C would not cause an initial energization of relay 12 for the effect of such a train upon the circuits would be merely to drop the armature 6¹ thus

breaking connection between wires 26 and 27, thus deenergizing relay 11 and dropping its armature 11¹, but such train would not, while on section C cause relay armature 5² to drop or arm 15 to make contact with contact 33.

The train which we have heretofore assumed to pass upon the rails of section A and then upon the rails of section B would, 10 while any part of the same was upon section B cause to be continued the energization of relay coil 12 through the stick circuit, as during all the time that it is upon block B relay 5 would be deenergized and 15 consequently relay coil 11 would be deenergized and armature 11¹ would make contact with wire 32 and as long as armature 11¹ makes contact with wire 32 after the relay coil 12 has once been energized, 20 the relay coil 12 will continue to be energized. As the train passes upon the rails of section C, the current from battery 9 would be shunted from the relay coil 6 and armature 6¹ would break contact between 25 wires 26 and 27 thus continuing the deenergization of relay coil 11 and the energization of relay coil 12 through its stick circuit and the train could be made to control relay coil 12 to any desired distance 30 beyond the section C in an obvious manner. As soon as the train passes out of section C the relay armature 6¹ would be raised and as the relay armature 5¹ was raised by the passing of the train from section B, a complete circuit would again be formed through the relay 11 energizing the same and causing armature 11¹ to be raised into contact with wire 21 which would break the stick circuit through the relay coil 12 heretofore 35 described and cause armature 12¹ and 12² to drop to their lower position as shown in the figure, so that the system would again be in the normal condition as shown in the figure. If while a train moving in the direction of the arrow D were upon the rails of sections B or C and a second train should approach in the direction of the arrow D and pass upon the rails of section A, the armature 4¹ would again be dropped and as 45 heretofore fully explained the armature 12² being in its upper position, a circuit would be formed as follows: positive terminal of battery 14, wires 18 and 40, armature 12², wire 41, mechanism of signal 10, wire 17, 50 armature 4¹ and wires 22, 23, 24 and 25 to the negative terminal of the battery. The current in the above traced path would cause the arm of the signal 10 to move to the 45° or caution position, so that the 55 train upon approaching the signal 10 would be confronted not with a full clear or 90° position aspect but with a 45° or caution aspect indicating that a train was in the block controlled by the signal and it would 60 be governed accordingly. If the second 65

train should pass upon the rails of section B and a third train should then approach in the direction of the arrow D and pass upon the rails of section A, it likewise would be given a 45° or caution aspect of the arm of the signal 10 unless all previous trains had passed beyond the limit of section C. The aspect given to a train following another train into the section B in the direction of the arrow D, not only indicates that a train is upon sections B or C, but it also indicates the equally important fact that the train which is upon sections B or C entered upon sections B or C from the left hand end as viewed in the figure, for as we have seen, 7 unless the first train did so enter section B, the relay coil 12 would not have been energized, consequently the armature 12² would not have been raised to its upper position and consequently the circuit through the 8 45° control wire 41 would not have been completed by the entrance of a subsequent train moving in the direction of the arrow D unto section A.

It is well understood by those skilled in the art that the mechanism for moving a single arm signal to two operated positions from a normal biased position can be used equally well to operate the arms of a 2-arm signal each to one operated position from their normal biased position so that it must be well understood that the 45° control wire 41 could convey current to another signal arm to move said signal arm from a normal biased position to an operated position.

Although applicant has hereinafter described his invention as applied to a normal danger signaling system, it is fully understood by those skilled in the art that by not using relay 4 and its controlled armature and the connection of wire 23 with wire 17 by means of wire 42 would transform applicant's embodiment shown from a normal danger system to a normal clear system, as shown by Fig. 2, and that if such change were made, the arm of signal 10 instead of remaining in its biased position would normally stand in the full clear or 90° position and that the entrance of a train upon section B moving in the direction of the arrow 1 D under such conditions would cause the arm of the signal to move to the 45° position and that the arm on signal 10 would move to the full normal or danger position only upon the movement of a train into section C when moving in the direction of the arrow E. It is furthermore to be observed that the aspects of the signal would either with the normal danger or the normal clear systems be identical and that under the same 1 conditions as regards the presence of a train which has passed the signal the aspect of the signal presented to an approaching train would in the two systems be identical.

It will be readily perceived by those 1

skilled in the art that relay 11 has been used merely because of the fact that the block controlled by the signal 10 includes two track circuit sections. It will be readily perceived by those skilled in the art that the principle underlying the use of circuit breaker 15 consists fundamentally of a circuit breaker which is governed as to its position by the condition of the circuit which controls the full clear aspect of the signal 10, and which requires for its movement from closed position a greater period of time than is required for a relay armature to fall by gravity upon its back contact upon the deenergization of the relay controlling the armature. It is also to be observed that what applicant has shown and described is simply a unit of a system, and in order to create a system, the unit would need to be duplicated, with the usual overlapping as is well understood by those skilled in the art.

Having particularly described the construction and operation of an embodiment of my invention and explained the operation and principle thereof, what I claim as new and desire to protect by Letters Patent, is:

1. In a railway signal system, a signal having a biased aspect and a plurality of operated aspects, a closed track circuit, a relay controlled by said closed track circuit, a normally closed circuit containing a second relay controlled by the first relay, a circuit including said signal controlled by said second relay, a normally open circuit controlled by said first relay including a third relay and a circuit breaker adapted to be closed in an operated aspect of the signal, said third relay adapted to be energized by the shunting of the track circuit when said circuit breaker is closed, a further normally open circuit including said third relay and its armature adapted to be closed when the track circuit is shunted and said third relay is energized adapted to maintain said third relay energized after said circuit breaker is opened while said track circuit is shunted, and a normally open circuit including said signal controlled by said third relay, means to furnish electrical energy to each of said circuits.

2. In a railway signal system, a block, a signal governing the entrance to one end of said block and adapted to have a normal biased aspect and a plurality of operated aspects, a closed circuited track circuit of which the rails of said block form a part, a source of energy in said circuit and a translating mechanism in said circuit, means controlled by the translating mechanism adapted for causing an operated aspect of said signal, a second translating mechanism means controlled by the first mentioned translating mechanism and the aspect of the

signal adapted for energizing the second translating mechanism and means actuated by the energization of said second translating mechanism to keep it energized while said first mentioned translating mechanism is deenergized, and means governed by said second translating mechanism adapted to cause another operated aspect of said signal.

3. In a railway signal system, a signal having a biased aspect and an operated aspect, a closed track circuit, a translating device controlled by the closed track circuit, a normally closed circuit containing a second translating device controlled by the first mentioned translating device, a circuit for controlling the operated aspect of the signal controlled by the second mentioned translating device, a normally open circuit controlled by the first mentioned translating device including a third translating device and a circuit controller adapted to be closed in the operated aspect of the signal, the third mentioned translating device adapted to be energized by the shunting of the track circuit when the circuit controller is closed, a circuit controller controlled by the third mentioned translating device, a normally open circuit including said third mentioned translating device and the circuit controller controlled thereby adapted to be closed when the track circuit is shunted and said third mentioned translating device is energized adapted to maintain said third mentioned translating device energized after said first mentioned circuit controller is opened while said track circuit is shunted, a normally open circuit for signaling controlled by said third mentioned translating device, means to furnish electrical energy to each of said circuits.

- ing device is energized and adapted to maintain the third mentioned translating device energized after the first mentioned circuit controller is opened while the second mentioned translating device is shunted, a fourth normally open circuit for signaling controlled by the third mentioned translating device and the first mentioned translating device, means to furnish electrical energy to each of said circuits.
5. In a railway signal system, a closed track circuit, a second closed track circuit, a normally closed circuit, means controlled by the said normally closed circuit for signaling, means controlled by said track circuits for governing said normally closed circuit, a normally open circuit including a relay, means for closing said normally open circuit controlled by said normally closed circuit, 10 means including an armature of said relay to keep the relay energized, means controlled by said relay for signaling.
6. In a railway signal system, a block, a signal mechanism governing the entrance 15 to one end of said block and adapted to give a normal indication and a plurality of operated indications, a closed circuited track circuit of which the rails of said block form a part, a source of energy in said circuit and a translating mechanism in said circuit, means controlled by the translating mechanism adapted for causing an operated indication of said signal mechanism, a second translating mechanism means controlled by 20 the first mentioned translating mechanism and the signal mechanism adapted for energizing the second translating mechanism and means actuated by the energization of said second translating mechanism to keep 25 it energized while said first mentioned translating mechanism is deenergized, and means governed by said second translating mechanism adapted to cause another operated indication of said signal mechanism.
- 45 7. In a railway signal system, a closed track circuit, a second closed track circuit, a normally closed circuit, means controlled by the said normally closed circuit for signaling, means controlled by said track circuits for governing said normally closed circuit, a normally open circuit including a
- relay, means for closing said normally open circuit controlled by said normally closed circuit and by the first mentioned closed track circuit, means including an armature 55 of said relay to keep the relay energized, means controlled by said relay for signaling.
8. In a railway signal system, a track circuited trackway, a normally closed circuit, means controlled by the said normally closed circuit for signaling, means controlled by said track circuited trackway for governing said normally closed circuit, a normally open circuit including a relay, 60 means for closing said normally open circuit controlled by said normally closed circuit, means including an armature of said relay to keep the relay energized, means controlled by said relay for signaling.
9. In a railway signal system, a track circuited trackway, a normally closed circuit, means controlled by the said normally closed circuit for signaling, means controlled by said track circuited trackway for 65 governing said normally closed circuit, a normally open circuit including a relay and two circuit controllers, one of said circuit controllers governed by the said track circuited trackway, the other of said circuit controllers governed by the normally closed circuit, means including an armature of 70 said relay to keep the relay energized, and means controlled by said relay for signaling.
10. In a railway signal system, a track circuited trackway, a normally closed circuit, means controlled by the said normally closed circuit for signaling, means controlled by said track circuited trackway for 75 governing said normally closed circuit, a normally open circuit including a relay, means including a circuit controller controlled by said normally closed circuit for closing said normally open circuit, means including an armature of said relay to keep 80 the relay energized, and means controlled by said relay for signaling.
